(57) **CLAIM**

The ornamental design for a computer mouse, as shown and described.

DESCRIPTION

The computer mouse is used or without a cable between the computer and the computer mouse. The computer mouse as shown in the drawings is producible with or without invisible-, or slightly visible push-buttons and/ or scroll-wheels. In the manufacturing process every technical configuration can be applied for the computer mouse. The shape can have every ornament and / or print on every side.

FIG. 1 is a rear view of a computer mouse showing my new design;

FIG. 2 is a front view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The claimed computer mouse is used in the design which looks like a round closing cap of a bottle with rounded notches.
